UNITED STATES PATENT OFFICE.

JAMES F. REED, OF SOMERSWORTH, NEW HAMPSHIRE.

TOP-ROLL CLEARGER FOR DRAWING-ROLLS.

No. 903,885.

Specification of Letters Patent.

Patented Nov. 17, 1908.

Application filed April 11, 1908. Serial No. 426,541.

To all whom it may concern:

Be it known that I, JAMES F. REED, a citizen of the United States, and resident of Somersworth, county of Strafford, State of New Hampshire, have invented an Improvement in Top-Roll Clearers for Drawing-Rolls, of which the following description, in connection with the accompanying drawing, is a specification, like letters on the drawing 10 representing like parts.

This invention has for its object the production of a novel and efficient top-roll clearer for the drawing-rolls of spinning or drawing frames, whereby the clearing operation is greatly improved and a much better quality of yarn or roving secured.

It is well known to those familiar with the practical operation of spinning and drawing frames that the percentage of fly 20 and dirt taken up from the back rolls is very small and can be easily taken care of, but the short fly and dirt collects in much greater quantity on the front top-roll, and much trouble has been experienced because of the 25 accumulation of waste between the front and middle rolls, and on the face of the front roll. This is caused by the parting of the sliver in the draft between the middle and front rolls, and the collection of waste 30 retards the motion of the middle roll and thereby results in uneven draft. Portions of the bunches of waste drop back into the stock causing bunches in the yarn or roving, and other portions are caught at the face of 35 the usual clearer board and on the crown of the front roll and form like a veil down the front, dropping and feeding back into the yarn or roving and resulting in bunches and breakage.

40 It is very difficult, with the clearer devices now in general use, to keep the rolls clean and to prevent the bunches of waste from getting into the yarn or roving. In my present invention I have overcome these objectionable features in a very simple and 45 efficient manner, by a combination of board and roll clearer-device utilizing a roll to clear the front drawing-roll and a board to clear the back rolls, the board preventing fly 50 and dirt from accumulating on the back rolls and keeping them clean while the waste taken from the front roll is wound in a lap on the clearer roll provided for the purpose.

The various novel features of my invention 55 will be fully described in the subjoined

specification and particularly pointed out in the following claims.

Figure 1 is a partial transverse section of a sufficient portion of a spinning or drawing frame, with one embodiment of my invention 60 applied thereto; Fig. 2 is a perspective detail of a portion of my novel top-roll clearer, detached.

The pedestal or stand 1 having a fixed bearing for the front lower roll 2, the middle 65 and back lower rolls 3, 4 supported in bearings on the head or cap 5, and the top rolls 6, 7, and 8 having their journals resting in the usual sockets in the cap-bar 9, Fig. 1, may be and are all of well known construction and operate in usual manner.

In the present embodiment of my invention I provide a clearer-board 10 having its under face covered with suitable clearer cloth 11, and resting on the middle and back 70 top-rolls 7 and 8, as shown in Fig. 1, the front edge of the clearer-board resting against upright lugs or stops on the cap-bar, one of such stops being shown at 12, Fig. 1. The front edge of the board is beveled at 13, to provide a clearance for the clearer-roll, to be described, and by reference to Fig. 1 it will be seen that the middle and back top-rolls are protected and kept clean 75 from fly and dirt by the clearer-board. Upon the top of the clearer-board, as herein shown, I mount light metal brackets 14, preferably longitudinally slotted at 15, Fig. 2, to receive the retaining screws 16, so that the brackets can be adjusted to suit or fit 80 different frames, or different distances between the front and middle top-rolls. Each bracket at its front end is bent downward and rearward, preferably, to form a substantially J-shaped guide 17, 18 the heel 18 85 being turned rearwardly toward the board, the free end of the bracket being upturned and elongated, at 19. The guides receive the journals 20 of the front clearer-rolls 21, which in practice may be made conveniently 90 of wood covered with felt, flannel, or other suitable material, as at 22, and herein I have shown the clearer-rolls connected in pairs, see Fig. 2. The clearer-rolls rest upon the front top-rolls and are rotated thereby, the 95 journals 20 loosely entering the guides 17 and being held thereby in proper position during the operation of the apparatus, the bevel 13 affording sufficient clearance for the rolls 21 and preventing any clogging. As 100 105 110 115

the fly and dirt gathers on the front top-roll 6 it is cleared therefrom and wound up in a film or lap on the clearer-roll, and as the lap increases in diameter the roll journals can 5 rise in the guides 17 without interfering with the efficiency of the clearing action.

There is very little friction due to the clearer-rolls, running as they do directly on the front rolls, and bunches cannot drop 10 back onto the yarn or roving nor can they clog up between the front and middle top-rolls.

When necessary the clearer-rolls can be removed for cleaning or other purposes without disturbing the clearer-board, or the 15 latter and the rolls can be removed simultaneously, as will be manifest, and the construction is so simple that there is nothing to get out of order.

20 I have found that a clearer device of the construction shown will run at least twenty-five times as long as the usual clearer devices before it is necessary to clean it. When the board is turned up the curved heels 18 of the 25 clearer-roll guides prevent the journals from falling out, the clearer-rolls returning to operative position when the board is replaced. By lengthening the uprights 19 at the front of the guides 17 the roll-journals 30 are held in place even should a very thick lap of waste be permitted to accumulate.

My invention is not restricted to the precise construction and arrangement herein shown and described as the same may be 35 modified or varied in different particulars by those skilled in the art without departing from the spirit and scope of my invention as set forth in the appended claims.

Having fully described my invention, 40 what I claim as new and desire to secure by Letters Patent is:—

1. In apparatus of the class described, in combination, a series of top drawing-rolls, a clearer-board coöperating with the middle 45 and back drawing-rolls, a removable clearer-roll coöperating with the front drawing-roll, and guiding means for the clearer-roll, mounted on the clearer-board.

2. In apparatus of the class described, 50 in combination, a series of top drawing-rolls, a clearer-board coöperating with the middle and back drawing-rolls, a clearer-roll coöperating with the front drawing-roll, and upright open guides for the journals of the 55 clearer-roll, adjustably attached to the clearer-board.

3. In apparatus of the class described, in combination, a series of top drawing-rolls, a

clearer-board coöperating with the middle and back drawing-rolls, a clearer-roll coöperating with the front drawing-roll, guiding means for the clearer-roll, and means to adjustably connect said guiding means with the clearer-board.

4. In apparatus of the class described, in 65 combination, a series of top drawing-rolls, a clearer-board coöperating with the middle and back drawing-rolls, a clearer-roll coöperating with the front drawing-roll, and open guiding connections between the 70 clearer-roll and board, said connections being curved rearwardly at their lower ends, whereby the roll and board may be removed simultaneously or the clearer-roll removed independently of the clearer-board.

5. A top-roll clearer for spinning and drawing frames, comprising a clearer-board, a clearer-roll to coöperate with and be rotated by the front top drawing-roll, guides for the clearer-roll carried by the clearer-board, and means to adjust the guides to 80 vary the distance between the clearer-roll and the board.

6. A top-roll clearer for spinning and drawing frames, comprising a clearer-board, 85 a clearer-roll to coöperate with and be rotated by the front top drawing-roll, and upright guides for the clearer-roll, open at their upper ends and curved rearwardly at their lower ends, said guide being mounted 90 on the clearer-board.

7. In apparatus of the class described, in combination, a series of top drawing-rolls, a clearer-board to rest upon and clear the middle and back drawing-rolls, forwardly 95 extended brackets on the clearer-board provided with guides open at their upper ends, and a clearer-roll having its journals loosely and removably entering the guides, said clearer-roll resting upon and clearing fly 100 and dirt from the front drawing-roll.

8. A top-roll clearer for spinning and drawing frames, comprising a clearer-board, a clearer-roll to coöperate with and be rotated by the front top drawing-roll, and 105 J-shaped guides for the clearer-roll, mounted on the clearer-board at the front thereof, the heels of the guides retaining the clearer-roll in place when the clearer-board is lifted.

In testimony whereof, I have signed my 110 name to this specification, in the presence of two subscribing witnesses.

JAMES F. REED.
